UNITED STATES PATENT OFFICE.

JOSEPH M. CHECK, OF WILKES-BARRE, PENNSYLVANIA.

HAT PROTECTOR.

Application filed November 3, 1921. Serial No. 512,440.

To all whom it may concern:

Be it known that I, JOSEPH M. CHECK, citizen of the United States, residing at Wilkes-Barre, in the county of Luzerne and State of Pennsylvania, have invented certain new and useful Improvements in Hat Protectors, of which the following is a specification.

The invention relates to hat protectors such as are used with straw hats and the principal object is to provide a hat protector which can be quickly secured to the brim of a straw hat, to shield same during a rain storm, and which thereafter can be conveniently folded and stowed anywhere on the person.

These and other objects will become apparent in the description to follow in which like-named characters in the specification will refer to the like-named parts in the drawing.

The drawing will be described briefly as follows:

Figure 1, is a perspective view showing part of the hat protector torn away to disclose the hat.

Figure 2 is a bottom plan view reduced and shows the attaching strips.

Figure 3 is a cross section of the same.

Figure 4 is an enlarged sectional view of the spring button securing means.

Figure 5 is a view of a modified form of securing means.

Referring to the drawing more in detail the numeral 10 represents the usual type of straw hat worn generally during the summer season, and having the hat protector thereon. The hat protector is preferably made of three pieces, the fabric of which consists of a close woven variety having the outer or exposed surface thereof coated with a water-proofing compound.

The numeral 11 indicates the fabric cov-

ering the upper surface of the crown of the hat and is joined to the fabric band 12 by means of the lap joint 13, is joined to brim cover 14 by means of lap joint 15, the outside element of the joint 15 being part of the fabric 12 and the inner element 14' being turned up from the brim cover as shown. It is apparent from the drawing that no seam is presented allowing rain to gain the lower surface 14, which covers the entire surface of the upper surface of the brim of the hat. Said fabric 14 has strips 17 sewn thereto extending over the edge 16 and adapted to have spring button elements 18 secured thereto. The hat 10 has holes punched thru the brim adapted to receive the sleeves 19, having a tapered hole 20 therein, the largest diameter of which is at the upper surface of the brim of the hat. It is apparent from Fig. 4, that when the spring ball 21 of the snap fastener elements 18 are inserted in the holes 20 on the under side of the hat they will form an effective securing means easily detached.

I claim:

1. In combination with a hat, a hat covering comprising a disc of waterproof material shaped to be disposed over the brim of the hat, said disc having an opening through which the crown of the hat extends, an upturned flange formed integral with said disc tightly fitting the crown, a band encircling said crown and flange, a cover over the top of the hat, a downturned flange formed at the edge of said cover overlying said band, strips secured to said disc, said strips extending under the brim of the hat, snap fastener elements carried by said strips, and engaging means for said fastener elements permanently fixed in the brim of the hat.

In witness whereof I affix my signature. JOSEPH M. CHECK.
